RATCHET GEAR MECHANISM

David Deane Panabaker, St. Mary's, Ontario,
Canada

Application August 21, 1936, Serial No. 97,277

6 Claims. (Cl. 74—124)

My invention relates to speed reducing gear mechanisms, and more particularly to speed reducing gear mechanism employing a ratchet gear which imparts an intermittent rotative movement to a driven shaft.

Heretofore ratchet gear mechanisms have been devised, particularly of the type employing ratchet pawls engaging with teeth in the periphery of a ratchet wheel, but the use of such mechanisms in industry has been severely limited, due in part at least to the fact that the ratchet means employed has been unduly large and complicated and has lacked the ruggedness and long operating life of equivalent means imparting a continuous rotative movement to the driven shaft. Moreover, the incorporation in such devices of the prior art of means for varying the ratio of speed reduction has heretofore further complicated and enlarged the structure, with a consequent further decrease in the desirability of the unit in industrial employment.

It is an object of my invention to provide a means for imparting an intermittent rotative motion at reduced speed to a driven shaft, which will be both compact and rugged, simple, economically manufactured and readily assembled, and which will have a long useful life at relatively heavy loads.

It is a further object of my invention to provide a reducing gear mechanism employing a ratchet gear with which is incorporated a simple, readily adjustable means for providing more than one ratio of speed reduction.

The features of my invention which are believed to be novel and patentable are set out with particularity in the claims appended hereto. For a better understanding of my invention and of the objects and advantages thereof, reference should now be had to the following particular description and to the drawings attached thereto, in which

Fig. 1 is an elevational drawing partly in section illustrating one form of my invention adapted for a constant ratio of speed reduction;

Fig. 2 is a sectional drawing on the line 2—2 of Fig. 1; and

Figs. 3 and 4 are respectively a plan view, and a sectional view similar to Fig. 2, of another form of my invention adapted to give a half speed and a zero speed ratio.

Referring now particularly to Figs. 1 and 2 I have shown the speed reduction ratchet gear mechanism of my invention mounted in a casing or box 1, which may be and preferably is made in a single casting and is provided with

suitable exterior apertured lugs 2 adjacent one wall thereof by means of which the unit may be bolted to a vertically extending wall. It may be desirable to provide a cover for the casing, and for this purpose there are provided the lugs 5 2a adjacent the top of the casing, each having a tapped hole therein for the reception of suitable securing screws. The output or driven shaft 3 of the mechanism of my invention is journaled at one end in a suitable bearing 4 provided in the front wall of casing 1, and is journaled at its other end in a sleeve 5 which is preferably integral with the ratchet wheel 6. The sleeve 5 in turn is journaled in a suitable bearing 7 provided in the rear wall of casing 1 and a driving overload protective connection is made between the sleeve 5 and shaft 3 by means of the soft steel shear pin 8 which extends through suitable apertures in both the sleeve 5 and shaft 3. The forward and rear 10 ends 9a and 9b respectively of the driven shaft 3 are formed into portions of non-circular cross section for the purpose of providing a ready means for connecting thereto the member to be driven thereby. The end 9a of shaft 3 is also 15 formed with a flange 10 and suitable washers 11 are provided between the flange 10 and the outer surface of casing 1 to form a dust protecting seal for the bearing 4.

The ratchet wheel 6 of suitable relatively large 30 diameter is preferably formed integral with the sleeve 5 but may be secured thereto in any manner so that rotation of the wheel 6 rotates the sleeve 5 thereby driving the shaft 3. Each face of the wheel 6 is provided with an annulus of 35 ratchet teeth 12, the operative tooth faces extending along radii of the wheel 6. Ratchet pawls 13 and 14 each in the form of a plate and each having an annulus of ratchet teeth 15 and 16 respectively, are located adjacent the working 40 faces of the ratchet wheel 6, the ratchet teeth 15 and 16 on the pawls 13 and 14 respectively cooperating with the teeth 12 on opposite faces of the wheel 6. Pawl 13 is provided with a bearing 17 journaled over the sleeve 5 and is biased 45 toward the adjacent face of the ratchet wheel 6 by means of the spring 18. Ratchet pawl 14 is similarly provided with a bearing 19 journaled over the shaft 3 and is biased toward the other face of the ratchet wheel by means of the 50 spring 20.

A second shaft 21 is mounted in casing 1 adjacent the periphery of ratchet wheel 6, with its axis extending parallel to that of the driven shaft 3. A pair of oppositely disposed eccentrics 22 55

and 23 are mounted for rotation on shaft 21, each located opposite one of the ratchet pawls 13 and 14. Ratchet pawl 14 is provided with a pair of laterally extending arms 24 and 25 formed integral therewith and spaced apart to form therebetween a slot of sufficient width to receive the eccentric 23, and the forward arm 25 is provided with a reinforcing rib 26. Pawl 13 is also provided with similar arms extending laterally therefrom and arranged to engage on opposite sides of the eccentric 22, and a reinforcing rib 27 is also provided on the forward arm 28 of this pawl. It will be understood that the shaft 21 may constitute the drive shaft of the mechanism, in which case a portion thereof would extend outside of the casing 1 for convenient connection to a source of rotative motion such as an electric motor and a suitable driving connection would be made between shaft 21 and the eccentrics. In the modification of my invention illustrated in Figs. 1 and 2, however, the shaft 21 is a countershaft on which are mounted the eccentrics 22 and 23 arranged to be driven by means of worm gear 29 engaging with a worm 30 on a drive shaft 31 which is mounted in suitable bearings in casing 1 and extends transversely of shaft 21. Conveniently the eccentrics 22 and 23 and the worm wheel 29 are made in a single casting and this casting is loosely mounted for rotation on the shaft 21. The drive shaft 31 extends outside of casing 1 and may be directly or otherwise connected to an electric motor (not shown) or other suitable means for providing rotative motion.

In operation the drive shaft 31 drives the eccentrics on the countershaft 21 at a suitable reduced speed through the worm 30 and worm wheel 29. The oppositely disposed eccentrics 22 and 23 in rotation about the axis of shaft 21 oppositely oscillate the ratchet pawls 13 and 14 alternately backward and forward, each pawl in its forward oscillation engaging with the teeth 12 on its side of the ratchet wheel 6 to thereby drive the shaft 3, and in a backward oscillation riding up the sloping surface of the teeth 12 against the bias of springs 18 and 20 respectively. The angle A through which each pawl is moved in each of its complete forward or backward oscillations is

$$50 \quad 2 \tan^{-1} \frac{e}{d}$$

e designating the eccentricity of the cams 22 and 23 and d the distance between the axes of shafts 21 and 3. Assuming that the pawl 13 is just beginning a forward oscillation and is in driving engagement with the teeth on the ratchet wheel, during the first half revolution of the eccentric 22 on shaft 21 the ratchet wheel will be turned through an angle A. During the next half revolution of the eccentrics on shaft 21, the ratchet wheel is driven through a further angle A by the pawl 14 and the pawl 13 is returned to its rearmost position to again engage the teeth of the ratchet wheel. Thus during a complete revolution of the eccentrics on shaft 21, the ratchet wheel is driven through an angle 2A. With the apparatus illustrated in Figs. 1 and 2 wherein the pawls are oppositely oscillated, that is one pawl is oscillated backward while the other is oscillated forward, and wherein each pawl engages the teeth on the ratchet wheel at the beginning of its forward oscillation, the angle between successive teeth on the same side of the ratchet wheel 75 can not be greater than 2A; and the number

of teeth N on one side of the ratchet wheel is given by

$$N = k \frac{360}{2A}$$

k being any integer. When *K*=1 or any other odd integer it will be apparent since the pawls are oppositely oscillated that the teeth on opposite sides of the ratchet wheel must be arranged in staggered relation (as shown in Fig. 1) whereas if *k*=2 or any other even integer the teeth on opposite sides of the ratchet wheel will be exactly opposite each other (as shown in Fig. 3).

It will be observed, in the case of Fig. 1, where-in *k*=1, that, if for any reason one of the pawls 13 or 14 should fail to be oscillated in the backward direction through the full angle A, the teeth thereon would not engage with a tooth face on the ratchet wheel 6, and the pawl would be subsequently oscillated idly in the forward direction. In the case of the modification of my invention shown in Figs. 1 and 2 this would result in a complete cessation of rotation of the ratchet wheel 6 and driven shaft 3. In Figs. 3 and 4 I have illustrated a mechanism similar to that shown in Figs. 1 and 2 but wherein means have been included to reduce or eliminate the backward throw of one or both pawls and wherein *k* has been selected as 2 in order to take advantage of the reduced backward oscillation of the pawls in order to obtain a half speed of the driven shaft, assuming a constant speed of the drive shaft.

As in Figs. 1 and 2, the modification of my invention shown in Figs. 3 and 4 comprises a driven shaft 3 having a ratchet wheel mounted thereon with ratchet teeth in each face thereof, a pair of ratchet pawls 13 and 14 in the form of plates mounted for oscillation about the axis of rotation of shaft 3 and provided with ratchet teeth adapted to engage with the teeth on the ratchet wheel, each pawl being spring pressed against one face of the ratchet wheel, a countershaft 21 on which are mounted for rotation a pair of eccentrics 22 and 23, and a drive shaft 31 provided with a worm 30 arranged to drive a worm wheel 29 mounted on the shaft 21. Each of the pawls 13 and 14 is provided with arms extending laterally adjacent to its respective eccentric, the forward arms of the pawls being provided with reinforcing ribs 26 and 27 respectively. In the embodiment of my invention shown in Figs. 3 and 4, however, the rear arm of pawl 14 is formed into a circular vertically extending socket 32 within which is received the end of a cylindrical rod 33. The rod 33 extends vertically beyond the top of casing 1 and is provided at its upper end with a lever 34 whereby it may be conveniently rotated in the socket 32. The rod 33 is also provided, adjacent the eccentric 23, with an offset surface 35 so arranged that when the rod 33 is turned to one position the distance between the surface 35 and the operating face of arm 25 is substantially equal to the diameter of the eccentric 23, and when rod 33 is turned to a position 90° from the first position, this distance is substantially greater than the diameter of the eccentric 23. Pawl 13 is likewise provided with a similar socket 36 receiving the rod 31 having control lever 38 and offset surface 39 and in Fig. 3 I have shown the rods 33 and 37 respectively in the two positions above referred to. Conveniently, means (not shown) may be provided on the rods 33 and 37 cooperating with the cover of casing 1 to posi-

tively hold the rods in one of their two positions.

The operation of the mechanism shown in Figs. 3 and 4 when both rods 33 and 37 are in the operative position, i. e. in the position of rod 5 33 in Fig. 3, is substantially the same as that of the mechanism of Figs. 1 and 2, each of the pawls being alternately oscillated backwards and forwards, each pawl alternately driving the ratchet wheel and driven shaft during its forward oscillation.

Due to the selection of the value 2 for k in the foregoing formula

$$N = \frac{k}{2A}^{360}$$

15 each pawl in its forward oscillation drives the ratchet wheel through an angle A , which is equivalent to one tooth space on the ratchet wheel, and in its backward oscillation rides idly over one tooth and engages the tooth second back of that it engaged for its previous forward oscillation. Thus when both pawls are operative, the shaft 3 is driven through an angle $2A$ for each complete revolution of the eccentrics about shaft 21.

25 Let it now be assumed that at the beginning of the forward oscillation of one pawl, the control lever for that pawl is moved to the inoperative position i. e. the position of rod 37 in Fig. 3. 30 During the next half revolution of shaft 21 the one pawl drives the ratchet wheel and shaft 3 through the angle A while the opposite pawl is being retracted through an equal angle, passing idly over one tooth on the ratchet wheel. During the next half revolution of the shaft 21 the 35 opposite pawl drives the ratchet wheel through an angle A , but, owing to the inoperativeness of the offset surface on the rod of the first pawl, this pawl is not retracted through the full angle A but through some angle less than A . As a 40 consequence the first pawl does not engage with a tooth face on the ratchet wheel and during the next half revolution of shaft 21 this pawl moves idly forward over a tooth surface on the ratchet wheel. During this half revolution of shaft 21, the ratchet wheel and shaft 3 are not turned, and the opposite pawl is retraced a full 45 angle A to engage with the next tooth on the adjacent face of the ratchet wheel. Thus under these conditions, during a complete revolution of the shaft 21, the ratchet wheel is rotated through an angle A only and a half speed is obtained.

If both control levers are at the same time in the inoperative position, it is obvious that a 50 zero speed is obtained, both pawls being thus made inoperative to drive the ratchet wheel. Such an adjustment is sometimes desirable where the motor used to drive the gear reduction mechanisms is also used to drive other mechanisms, the 55 operation of which may be desired independently of that of the gear reduction mechanism. In the mechanism shown in Figs. 1 and 2 a zero speed adjustment might be obtained by providing one of the pawls with a control lever as in Figs. 3 and 4. In that case the reduction of the backward throw of one pawl would make both pawls 60 completely inoperative to drive the ratchet wheel.

Although in the foregoing description I have selected the values 1 (Figs. 1 and 2) and 2 (Figs. 3 and 4) for k in the formula

$$N = \frac{k}{2A}^{360}$$

70 and have pointed out how a half and a zero speed of the driven shaft may be obtained, it will be 75 apparent that other fractional speeds of the

driven shaft may be obtained by suitably selecting a value for k and varying the backward throw of one or both pawls. I do not wish to be limited to the specific modifications shown, and in the appended claims I aim to cover all such variations or modifications of my invention as fall within the time spirit or scope of my invention.

What I claim as new and desire to secure by Letters Patent of the United States, is:

1. A ratchet gear reduction mechanism comprising a shaft, a ratchet wheel mounted on said shaft and having teeth in the face thereof, a pawl mounted for oscillation about the axis of said shaft adjacent the face of said ratchet wheel means for biasing said pawl into engagement with the teeth on said face, a second shaft having its axis extending substantially parallel to that of said first shaft, an eccentric mounted on said second shaft for rotation about the axis thereof, means for rotating said eccentric, means extending from said pawl and having a surface adjacent one side of said eccentric whereby said pawl is oscillated in a forward direction as said eccentric is rotated, and means extending from said pawl and having a surface adjacent the other side of said eccentric whereby said pawl is oscillated in a backward direction as said eccentric is rotated, said last-named means including a rod mounted in a socket formed in said pawl and having an offset surface adapted to co-operate with said eccentric, said rod being rotatable in said socket about its longitudinal axis to vary the co-operative engagement of said offset surface and said eccentric, whereby the angle through which said pawl is oscillated to drive said ratchet wheel may be varied.

2. A ratchet gear reduction mechanism comprising a shaft, a ratchet wheel mounted on said shaft and having teeth in the face thereof, a pawl mounted for oscillation about the axis of said shaft adjacent the face of said ratchet wheel means for biasing said pawl into engagement with the teeth in said face, a second shaft having its axis extending substantially parallel to that of said first shaft, an eccentric mounted on said second shaft for rotation about the axis thereof, means for rotating said eccentric, means extending from said pawl and having a surface adjacent one side of said eccentric whereby said pawl is oscillated in a forward direction as said eccentric is rotated, means extending from said pawl and having a surface adjacent the other side of said eccentric whereby said pawl is oscillated in a backward direction as said eccentric is rotated, said last-named means including a rod mounted in a socket formed in said pawl and having an offset surface adapted to co-operate with said eccentric, said rod being rotatable in said socket about its longitudinal axis to move said offset surface into and out of co-operative engagement with said eccentric whereby said last named means extending from said pawl may be made ineffective to oscillate said pawl through a complete backward oscillation.

3. A ratchet gear reduction mechanism comprising a shaft, a ratchet wheel mounted on said shaft and having teeth in each face thereof, a pawl mounted adjacent each face of said ratchet wheel for oscillation about the axis of said shaft, and having ratchet teeth adapted to engage with the teeth in the adjacent face of said wheel, a second shaft, an eccentric mounted on said second shaft opposite each of said pawls, means to rotate said eccentrics about the axis of said sec-

ond shaft, a pair of arms extending from each of said pawls and having surfaces adjacent opposite sides of said eccentric whereby when said eccentric are rotated said pawls are oscillated through a given angle, one of said arms including a rod mounted at one end in a socket formed in the pawl and having an offset surface arranged to co-operate with the respective eccentric, said rod being rotatable about its longitudinal axis in said socket to vary the cooperative relation between said offset surface and said eccentric whereby when said eccentric are rotated one of said pawls may be arranged to oscillate through an angle less than said given angle.

4. In a ratchet gear reduction mechanism comprising a ratchet wheel having teeth in a face thereof, a pawl mounted adjacent to the face of said ratchet wheel for oscillation about the axis of rotation of said wheel, a shaft, an eccentric mounted for rotation about the axis of said shaft, means for rotating said eccentric and a pair of arms extending from said pawl and having surfaces adjacent opposite sides of said eccentric whereby when said eccentric is rotated said pawl is oscillated through a given angle, one of said arms including a rod mounted at one end in a socket formed in said pawl and having an offset surface arranged to co-operate with said eccentric, said rod being rotatable about its longitudinal axis in said socket to vary the co-operative relation between said offset surface and said eccentric.

5. A ratchet gear reduction mechanism comprising a casing, a shaft mounted at one end for rotation in a wall of said casing, a sleeve mounted for rotation in the opposite wall of said casing, the other end of said shaft being journaled within said sleeve, means located outside of said casing and securing said shaft and sleeve together and forming a driving overload protective connection therebetween, a ratchet wheel secured to one end of said sleeve and mounted within said casing about said shaft and having ratchet teeth in each face thereof, a ratchet pawl plate mounted for oscillation about the axis of said shaft adjacent each face of said ratchet wheel and having teeth adapted to co-operate with the teeth

in the adjacent face of the wheel, means for biasing each of said pawl plates into engagement with the ratchet wheel, a second shaft mounted in said casing with its axis substantially parallel to that of said first shaft, an eccentric mounted on said second shaft opposite each of said pawl plates, means for rotating said eccentric about the axis of said second shaft, and a pair of arms extending from each of said pawl plates and engaging on opposite sides of the respective eccentric whereby as said eccentric are rotated said pawl plates are oscillated to drive said ratchet wheel and first shaft.

6. A ratchet gear reduction mechanism comprising a casing, a shaft mounted at one end for rotation in one wall of said casing, a sleeve mounted for rotation in the opposite wall of said casing, the other end of said shaft being journaled within said sleeve, a shear pin securing said shaft and said sleeve together and extending therethrough outside of said casing, a ratchet wheel formed integral with said sleeve and mounted within said casing about said shaft and having ratchet teeth in each face thereof, a ratchet pawl plate mounted on said sleeve adjacent one face of said ratchet wheel and having teeth adapted to cooperate with the teeth in the adjacent face of said wheel, another ratchet pawl plate mounted on said shaft adjacent the other face of said wheel and having teeth adapted to cooperate with the teeth in the adjacent face of said wheel, means for biasing each of said pawl plates into engagement with said ratchet wheel, a second shaft mounted in said casing with its axis extending substantially parallel to that of said first shaft, an eccentric mounted on said second shaft opposite one of said pawl plates, an oppositely disposed eccentric mounted on said second shaft opposite the other of said pawl plates, means for rotating said eccentric in unison about the axis of said second shaft, and a pair of arms extending from each of said pawl plates and engaging on opposite sides of the respective eccentric whereby as said eccentric are rotated said pawl plates are oppositely oscillated to alternately drive said ratchet wheel and first shaft.

D. DEANE PANABAKER.
